DESIGN FOR AN INKSTAND.

The Schedule referred to in these Letters Patent and making part of the same

I, ALONZO FRENCH, of Philadelphia, in the county of Philadelphia, and State of Pennsylvania, have invented and produced a new and original Design for an Inkstand, of which the following is a specification, reference being made to the accompanying drawings.

Figure 1 is a perspective view of an inkstand, made with a depression in the upper surface, extending around the top of the stand for the cork to rest in, as at *a*.

The bottom has three spaces, as at *b*, so that dust may be removed by blowing under it.

I claim, as my invention—

The design for an inkstand, as shown.
